(57) **CLAIM**

The ornamental design for a center extender for rear of truck roof, as shown and described.

DESCRIPTION

FIG. 1 is a rear perspective view of a center extender for rear of truck roof showing our new design;

FIG. 2 is a rear elevational view of the center extender for rear of truck roof of FIG. 1;

FIG. 3 is a front elevational view of the center extender for rear of truck roof of FIG. 1;

FIG. 4 is a top plan view of the center extender for rear of truck roof of FIG. 1;

FIG. 5 is a bottom plan view of the center extender for rear of truck roof of FIG. 1; and,

FIG. 6 is a left side elevational view of the center extender for rear of truck roof of FIG. 1, the right side elevational view being mirror symmetrical to FIG. 6.

The broken line showing of a portion of a truck roof is for the purpose of illustrating environmental structure and forms no part of the claimed design.
